[57] CLAIM

The ornamental design for a bulk food dispenser, as shown.

DESCRIPTION

FIG. 1 is a front elevational view of a bulk food dispenser showing my new design;

FIG. 2 is a top plan view thereof;

FIG. 3 is a rear elevational view thereof;

FIG. 4 is a left side elevational view thereof;

FIG. 5 is a right side elevational view thereof;

FIG. 6 is a front elevational view of a second embodiment of that shown in FIG. 1;

FIG. 7 is a top plan view thereof;

FIG. 8 is a rear elevational view thereof;

FIG. 9 is a left side elevational view thereof;

FIG. 10 is a right side elevational view thereof;

FIG. 11 is a perspective view of the embodiment of the dispenser shown in FIG. 1; and

FIG. 12 is a perspective view of the embodiment of the dispenser shown in FIG. 6.

The bottom surface of the dispenser is plain and unornamental.
